(57) **CLAIM**

The ornamental design for a parking block, as shown and
described.

DESCRIPTION

FIG. 1 is a front view of the parking block according to a first
embodiment of the present invention;

FIG. 2 is a top plan view of the parking block according to
the first embodiment;

FIG. 3 is a rear view of the parking block according to the
first embodiment;

FIG. 4 is a bottom view of the parking block according to the
first embodiment;

FIG. 5 is a right side view of the parking block according to
the first embodiment, note that the left side is a mirror image
of the right side;

FIG. 6 is an enlarged sectional view taken along line A—A
in FIG. 1;

FIG. 7 is an enlarged sectional view taken along line B—B
in FIG. 1; and,

FIG. 8 is an enlarged sectional view showing the parking
block according to the first embodiment in a use condition.
